(57) **CLAIM**

We claim the ornamental design for a filter element, as shown.

DESCRIPTION

FIG. 1 is a front perspection view of filter and lid with measuring device

FIG. 2 is a rear perspection view thereof

FIG. 3 is a front plan view thereof

FIG. 4 is a rear plan view thereof

FIG. 5 is a left plan view thereof

FIG. 6 is right plan view thereof

FIG. 7 is a top plan view thereof

FIG. 8 is a bottom plan view thereof

FIG. 9 is a front perspection view of filter and lid without measuring device

FIG. 10 is a rear perspection view thereof

FIG. 11 is a front plan view thereof

FIG. 12 is a rear plan view thereof

FIG. 13 is a left plan view thereof

FIG. 14 is a right plan view thereof

FIG. 15 is a top plan view thereof

FIG. 16 is a bottom plan view thereof

FIG. 17 is a front perspection view of lid with measuring device

FIG. 18 is a rear perspection view thereof

FIG. 19 is a front plan view thereof

FIG. 20 is a rear plan view thereof

FIG. 21 is a left plan view thereof

FIG. 22 is a right plan view thereof

FIG. 23 is a top plan view thereof

FIG. 24 is a bottom plan view thereof

FIG. 25 is a front perspection view of lid without measuring device

FIG. 26 is a rear perspection view thereof

FIG. 27 is a front plan view thereof

FIG. 28 is a rear plan view thereof

FIG. 29 is a left plan view thereof

FIG. 30 is a right plan view thereof

FIG. 31 is a top plan view thereof; and,

FIG. 32 is a bottom plan view thereof.
